FRANK L. CAPPS, OF BRIDGEPORT, CONNECTICUT, ASSIGNOR TO AMERICAN GRAPHOPHONE COMPANY, OF BRIDGEPORT, CONNECTICUT, A CORPORATION OF WEST VIRGINIA.

PRODUCTION OF DISK SOUND-RECORDS.

1,107,491.

Specification of Letters Patent. Patented Aug. 18, 1914.

Application filed October 28, 1912. Serial No. 786,100.

To all whom it may concern:

Be it known that I, FRANK L. CAPPS, a citizen of the United States of America, and a resident of Bridgeport, Fairfield county, 5 Connecticut, have invented a new and useful Improvement in the Production of Disk Sound-Records, which invention is fully set forth in the following specification.

This invention relates to improvements in 10 means for producing disk sound-records, and comprises the use of a detachable centering-pin carried by one of the dies between which the disk records are pressed. Heretofore, in pressing-up disk sound-records, a unitary centering-pin is secured rigidly to one of the dies, passing through the 15 registered holes in the center of the two matrices (or in the one matrix and the smooth back-plate, in case of a single-faced record) and entering a central hole in the 20 other die. After the record has been pressed, this pin seems to serve to bind the parts together; at any rate it has been necessary to resort to considerable hammering to 25 separate them in order to remove the record. This not only requires time and strength, but often causes injury to the parts, because small portions of the record-material are 30 liable to find lodgment between the adjacent faces of the matrix and the record, thereby permanently defacing the matrix as well as the record by producing therein bruised spots or dents. A record so defaced 35 has to be thrown into the scrap heap, as its reproduction would be attended by disagreeable snappy noises which impair, if they do not entirely destroy, the quality of the reproduction. But more serious than the loss 40 of such defaced record, however, is the loss of the matrix itself,—such dents and bruises rendering it worthless for further use.

The object of my invention, then, is to dispense with the hammering heretofore resorted to, to facilitate the removal of the 45 pressed record from the dies and matrices in which it has been pressed-up, to increase the percentage of perfect records so pressed, and to prolong the life of the matrices.

The invention will best be understood by 50 reference to the annexed drawing in which—

Figure 1 is a sectional view through the central portions of two dies with their matrices and the interposed record or record-material, showing in place the preferred

embodiment of my novel detachable centering-pin; and Fig. 2 is a perspective view of the two members of the two-part centering-pin which constitutes the preferred form of detachable pin.

In the drawings, 1 represents the lower die, and 2 the lower matrix whose matrix-surface lies uppermost.

3 represents the upper die, and 4 the upper matrix whose matrix-surface lies downward.

5 represents the interposed record-material or a portion of a pressed disk-record. The stationary member of the two-piece centering-pin is secured to the center of the lower die 1, and having the stem 6, preferably tapered or conical, rising to a height sufficient to penetrate the two matrices and the record, and in line with the hole in the upper die.

7 is the removable member, a shell adapted 75 to fit over the stem 6 and to fit snugly within the usual central holes in the matrices. The exterior of this detachable member 7 may be cylindrical, but preferably it also is slightly tapered to facilitate its removal 80 from the matrices and the ultimate pressed record.

In operation, the lower die 1 is laid with its stationary stem 6 projecting upward, and the removable member 7 is then put in 85 place thereon; next the lower matrix 2 is placed thereon with its face uppermost, the removable member passing snugly through the usual central aperture in said matrix; then the record-material (whether a homogeneous or laminated record is to be produced) is placed on the face of the matrix 2 in such manner that it surrounds the member 7; next the upper die 3 and its matrix 4 are properly located, with the face of said 90 matrix downward and with their central apertures alined with member 7; and all the assembled parts (dies, matrices, and record-material) are then placed in a suitable (hydraulic) press, and the record is pressed up 100 in the well-known manner. After the pressing is completed, the upper die 3 is readily pried off; then the upper and lower matrices with the record between them are simultaneously lifted from the lower die, the 105 shell 7 separating easily from the stationary pin 6 and coming away readily with the matrices and record; and, finally, the shell

7 is driven out, as by a tap on its upper end with a hammer, whereupon the two matrices are easily separated from the record.

By the use of my invention the time required for removing the pressed record from its matrices and dies is very much shortened, the hammering now necessary to separate the parts is entirely avoided, and the record is at all times protected by its matrices until 10 it is merely lifted out from between them; and neither the record nor the face of either matrix has opportunity to become dented or bruised. As a consequence, the percentage of imperfect records is greatly decreased, 15 and the life and usefulness of the matrix is greatly increased.

It is to be understood that my invention may be employed with two matrices 2 and 4, for pressing-up double-faced records, or 20 with one matrix and a smooth platen, for pressing-up single-faced records; and that changes may be made in the embodiment set forth without departing from the spirit of my invention, which consists broadly in employing a detachable member that acts, during the pressing, as an ordinary rigidly-

secured centering-pin; but when the pressing has been completed and the parts are to be separated, the detachable member comes off with the matrices and record. 30

Having thus described my invention, I claim:

In a device for pressing disk sound-records, the combination of a die, a pin protruding therefrom and with a sleeve carried 35 removably thereon to constitute a centering-member, a plate passing freely but snugly over the two-part centering-member aforesaid to rest against said die, said sleeve adapted to come in direct contact with the record-material and to be clamped by the pressed record and adapted to be removed from said pin by the removal of the pressed record. 40

In testimony whereof I have signed this 45 specification in the presence of two subscribing witnesses.

FRANK L. CAPPS.
